(57) **CLAIM**

The ornamental design for a bicycle as shown and described.

DESCRIPTION

FIG. 1 is a top, front and right side perspective view of a rear end of a bicycle;

FIG. 2 is a right side elevation view thereof;

FIG. 3 is a top, front and left side perspective view thereof;

FIG. 4 is a left side elevation view thereof;

FIG. 5 is a front elevation view thereof; and,

FIG. 6 is a top plan view thereof.

The broken dashed lines showing components included for the purpose of illustrating environmental structure and forms no part of the claimed design.

1 Claim, 6 Drawing Sheets
